of Delaware

Filed June 21, 1963, Ser. No. 75,465

Term of patent 14 years

(Cl. D58—26)

FIG. 1

FIG. 2

FIG. 3

FIG. 4

FIG. 1 is a front top perspective view of a combined closure, lipstick holder and mirror, showing my new design;

FIG. 2 is an exploded front top perspective view thereof;
The portions shown in broken lines are for illustrative purposes only.

This application is a continuation-in-part of my application Serial No. D. 70,117, filed May 14, 1962, and now abandoned.

I claim:

The ornamental design for a combined closure, lipstick holder and mirror, as shown and described.
